WITNESS:

Patented Feb. 12, 1924.

UNITED STATES PATENT OFFICE.

ALLEN A. VAN ORSDALE, OF PHILADELPHIA, PENNSYLVANIA.

VIBRATORY LUBRICATOR.

Application filed September 26, 1921. Serial No. 503,229.

To all whom it may concern:

Be it known that I, ALLEN A. VAN ORSDALE, a citizen of the United States, residing at Philadelphia, in the county of Philadelphia and State of Pennsylvania, have invented new and useful Improvements in Vibratory Lubricators, of which the following is a specification.

This invention relates to lubricators or automatic oilers and it has more particular reference to devices of the kind in which the emission or discharge of the lubricant is automatically controlled consequential upon the vibrations surrounding and communicated directly to said lubricator. More especially this invention relates to automatic lubricators which are characterized by a spring influenced discharge valve and it has for its primary object the provision of an improved type of controlled and regulatable lubricator for use upon machines or moving parts thereof which are susceptible to constant and varying vibrating disturbance.

Another object of this invention is to provide an automatic vibratory actuated lubricator of novel structure that is so adapted when desired to make easy the successful cleansing of the bearing or other part on which it is mounted without emptying, disturbing any of the contents, or removing said lubricator.

A further object of this invention is the provision of a highly sensitive vibratory lubricator that is easily regulatable to automatically meet requisite needs and when so required.

A still further object is to provide a novel form of vibratory lubricator which will automatically operate with equal success with an oil of low viscosity as with an oil having a higher viscosity.

Still further this invention has for objects the provision of a vibratory lubricator comprising but few and easily manufactured parts that can be readily assembled and adjusted, and which is so constructed that dirt or grit cannot impair or affect its successful operation in that the valve proper and its seat are so fashioned that it is impossible for the latter to hold or permit the adherence thereto of any matter which might prevent said valve from properly seating whereby loss or draining away of the lubricant or flooding of the bearing or other part

to which the device may be applied is effectively prevented.

With the foregoing and other objects in view as will become clearly apparent from the following description this invention consists primarily in providing a vibratory lubricator the upwardly seating valve whereof is formed with a hollow adjustable stem, means being associated therewith whereby the bore thereof can be moved into direct registering axial alignment with the discharge duct when desired. The invention also further consists in certain novel features of construction, combinations and arrangements of parts hereinafter fully described and more specifically defined by the appended claims.

In the further disclosure of the invention reference is to be had to the accompanying sheet of explanatory drawings constituting a part of this specification, and in which like characters of reference designate the same or corresponding parts in all the views.

Figure 1 is a central vertical section through a vibratory lubricator embodying the essential features of this invention.

Figure 2 is a top plan view of the same with a fragmentary portion removed to disclose the underlying structure.

Figure 3 is a section taken substantially on the line 3-3 in the preceding figure.

Figure 4 is an exaggerated fragmentary sectional detail showing the lubricator valve in open position.

Figure 5 is a corresponding exaggerated sectional detail illustrating the position of the vibratory valve and associated parts under flushing conditions.

Figure 6 is a similar sectional view to Figure 1 of a slightly modified form of the invention; and,

Figure 7 is illustrative of the application of this invention to a shackle bolt.

Referring more particularly to the views the oil cup or body portion proper of my improved vibratory lubricator is designated by the numeral 8 and said body portion is formed with a funnel-shaped bottom 9 adapted to seat leak-proof between an inner similarly shaped bottom 10 and the correspondingly flared upper inner part 11 of the hexagonal connecting member 12 which is externally screw-threaded at 13 for insertion into the bearing or part to be lubricated.

It is also to be particularly noted that the inner funnel shaped bottom 10 is provided with an exteriorly screw-threaded shank 14 for insertion in the correspondingly threaded bore 15 of the connecting member 12. The oil cup or body 8 is appropriately closed by a lipped cover 16 having an outwardly projecting and upwardly curved tongue 17 for engagement in a hasp 18 integral with the upper part of said cup or body. Diametrically opposed to the aforesaid tongue 17 is a downwardly rolled catch 19 adapted for snapping or gripping co-operation with the beaded part 20 provided for the purpose diametrically opposite to the aforesaid hasp 18 on the cup or body 8.

The valve seat consists of a tubular nipple 21 seated frictionally tight in the bore 22 of the aforesaid shank 14 and it is formed with an upwardly flared part or seating shoulder 23, whilst its top face 24 is finished off square with the longitudinal axis of its bore 25 and is of a diameter to register with the lubricant discharge duct 26. Upwardly seating on the flared part or valve seat proper 23 is the corresponding flared inner end 27 of the lower or valve section 28 of an exteriorly screw-threaded tubular stem 29, said stem 29 being threaded into the section 28 after the tubular nipple 21 has been firmly secured in the bore 22. In order to provide an efficient means for normally seating the valve section 28 on its seat 23 there is interposed between the inner concave part 30 of the inner bottom 10 and a nut or threaded collar 31 on the tubular stem 29 a compression spring 32, it being perfectly obvious that this spring functions to hold the valve section 28 on its seat 23 and that by manipulating the nut or collar 31 up or down the stem 29 its sensitivity may be varied or accurately adjusted to desired requirements. Cross cuts or radial grooves 33 may be provided in the nut or collar 31 whereby it can be more easily manipulated.

In the modified form of the invention shown by Figure 6 it will be seen that the valve section 28' is considerably extended, and that the spring 32' is housed therein being interposed between a shoulder 34 on the upper end of the tubular nipple 21 and a corresponding shoulder 35 at the inner end of the tubular screw-threaded insert 36 at its upper end. In this instance the adjustment of the spring 32' is effected by screwing the tubular insert 36 inwards or outwards relative to the valve section 28' as will be perfectly obvious.

In Figure 7 I have illustrated the applicability of my improved vibratory lubricator to a shackle bolt 37 and it is here most particularly emphasized that the proportions and sizes of the various parts in Figures 1 to 6 inclusive, have been drawn three

to four times their actual size in order to clearly illustrate their respective relation and for a clearer comprehension of their functioning.

Briefly described the operation of the improved vibratory lubricator is as follows: Assuming that the lubricator has been filled with oil as shown in Figures 1 and 6 it will be self-evident that when there is no surrounding or communicated vibrations or joltings the tubular stem 29 and connected valve section 28 will remain vertically poised as shown by Figure 1 with the said valve section in close engagement on its seat 23 thereby preventing the discharge of the oil therethrough and to the discharge duct 26. On the other hand whenever vibration is communicated to the lubricator it will be clear that the tubular stem 29 and connected valve section 28 will be rocked to a greater or lesser degree according to the intensity of said vibrations which will result in the unseating of the valve section 28 as shown in Figure 4 whereupon the oil will percolate or flow through the flared inlet 38, and enter the bore 25 of the nipple 21 in sufficient quantity to lubricate the bearing or other part on which the device is installed. Obviously according to the sensitivity of the spring 32 or its degree of regulation, the tubular stem will rock more or less rapidly whereby the lubricant fed through the discharge duct 26 can be controlled as desired, and it will be apparent that when the vibrations cease the valve section 28 will be automatically reseated under the action or recoil of said spring 32. Still further it is to be observed that by removing the lipped cover 16 and pressing down on the head of the tubular stem 29 the valve section can be seated on the hereinbefore referred to concave part 30 as shown by Figure 5 thereby effectively cutting off any tendency for the lubricant to flow out of the lubricator whereupon a suitable cleaning fluid or oil can be forced down the bore 35 of said stem and through the discharge duct 26 for flushing or thoroughly cleansing the moving part without in any way disturbing the contents of the lubricator. Another advantage accruing to my novel construction of vibratory lubricator is the fact that whenever there is an excess of lubricant or oil in a bearing or other moving part on which the device is used and a back pressure is caused for some unforeseen reason the surplus oil or lubricant will be forced back up through the duct 26 and nipple 21 past the valve 28 and returned into the oil cup or body 8, from whence it can be re-discharged again as hereinbefore set forth. Still further it is to be remarked that by the peculiar arrangement and disposition of the several parts the pressure above the lubricant level in the cup or body 8 will be the same as

that of the bearing or other moving part supplied therefrom, whilst when the vibratory lubricator comes to rest there will be a slight "lag" of lubricant that will be fed 5 into the bearing or other moving part after said part ceases motion which will ensure ease in restarting.

By reason of tubular nipple 21, which projects upwardly from the bottom of the oil 10 reservoir, dirt and sediment in the oil are prevented from lodging on the valve seat and interfering with the valve action, such dirt settling to the bottom of the cup below the level of the valve.

15 From the foregoing it will be clearly apparent that by my invention there is provided an exceedingly simple and efficient vibratory lubricator for use on machinery and moving parts subject to constant and 20 variable degrees of vibration, and whilst there has been shown and described the best form thereof at present known to me the same is not to be construed as conclusive, as it will be self-evident that many detail 25 changes or variations may be effected without departing from the true spirit and intent of the invention, therefore, the right is hereby reserved to make such changes and other modifications as fairly lie within the 30 scope of the appended claims.

Having described my invention, what I claim as new and desire to secure by Letters Patent is:

1. A vibratory lubricator comprising a 35 body portion having an axially holed bottom, an inner bottom having an extension for passage through the aforesaid bottom, a connecting member for coupling said inner bottom and body portion together, a valve 40 seat elevated above said bottom, an upwardly seating valve having a tubular stem, and compression means normally holding said valve to its seat but permitting of its displacement relative thereto.

45 2. A vibratory lubricator comprising a body portion having a centrally holed bottom, an inner bottom having an extension for passage through the centrally holed bottom, a connecting member for connecting 50 said inner bottom and body portion together, an upset tubular nipple projecting upwardly from the inner bottom and having a valve seat integral therewith, an upwardly seating valve having a tubular stem, and a compression spring normally holding said 55 valve to its seat but permitting of its free oscillation.

3. A vibratory lubricator comprising a 60 tubular body portion having a funnel shaped bottom, an inner bottom having an extension for passage through the funnel shaped bottom, a connecting member for clamping said inner bottom and body portion firmly together, an axially central tubular nipple 65 projecting upwardly from the inner bot-

tom and having a valve seat at its upper part, an adjustable upwardly seating valve having a tubular stem, and a compression spring normally holding said valve to its seat but permitting of its free oscillation. 70

4. A vibratory lubricator comprising a tubular body portion having a funnel shaped bottom, an inner bottom having an extension for passage through the funnel shaped bottom, a connecting member for clamping 75 said inner bottom and body portion firmly together, an axially central tubular nipple firmly seated in the inner bottom and having a valve seat at its upper part, an adjustable upwardly seating valve having a tubular 80 stem, and a compression spring normally holding said valve to its seat, said valve being adapted for axial longitudinal movement whereby its bore can be brought into registry and axial alignment with the afore- 85 said tubular nipple.

5. A vibratory lubricator comprising a tubular body portion having a funnel shaped bottom, an inner bottom having an extension for passage through the funnel shaped bottom, an internally axially central concave part, a connecting member for clamping said inner bottom and body portion firmly together, an axially central tubular nipple seated in the inner bottom and having a valve seat at its upper part, an adjustable upwardly seating valve having a tubular 90 stem, and a compression spring seating on the aforesaid concave part and serving to normally hold the valve to its seat but permitting of its free oscillation. 95

6. A vibratory lubricator comprising a tubular body portion having a funnel shaped bottom, an inner bottom having an extension for passage through the funnel shaped bottom, an internally axially central concave part, a connecting member for clamping 100 said inner bottom and body portion firmly together, an axially central tubular nipple firmly seated in the inner bottom and having a valve seat at its upper part, an upwardly seating valve comprising an externally threaded tubular stem and a valve section having a flared inner end constituting the valve proper, a compression spring seating between the aforesaid concave part and an adjustable collar threaded on said tubular stem, said spring serving to normally hold the valve to its seat but permitting of its 110 free oscillation. 115

7. A lubricator comprising a nipple projection upwardly from the bottom thereof and having a valve seat portion, and a pen- 120 dular sleeve surrounding the nipple and having a valve portion cooperating with 125 said seat portion.

8. The combination with a lubricator cup having a centrally holed bottom and connected attaching means of an upwardly ex- 130 tends tubular nipple having a valve seat.

an upwardly seating valve comprising an externally threaded tubular stem and a valve section having a flared inner end constituting the valve proper, and compression means normally holding said valve to the seat but permitting of its displacement relative thereto.

9. A vibratory lubricator comprising a hollow body portion having a perforated bottom, an inner bottom member therein having an extension passing through the aforesaid bottom, a connecting member for coupling said inner bottom member and the body portion together, a tubular nipple projecting upwardly from the inner bottom member having a valve seat thereon, an upwardly seating valve plunger having a tubular stem, and means normally holding said valve to its seat but permitting its partial displacement therefrom when the lubricator is vibrated.

10. A lubricator comprising a nipple projecting upwardly from the bottom thereof and having valve seat portion, and an upwardly seating vibratory valve means cooperating with said seat portion.

11. A lubricator comprising a nipple projecting upwardly from the bottom thereof and having a downwardly disposed valve seat portion on its upper end, and a vibratory sleeve surrounding the nipple and the seat portion, and having an upwardly seating annular valve portion cooperating with said seat portion.

12. A lubricator comprising a nipple projecting upwardly from the bottom thereof and provided at its upper end with an annular shoulder forming a valve seat, a vibratory sleeve surrounding the nipple and the shoulder and provided at its lower end with an inwardly disposed annular rib forming an upwardly seating valve portion cooperating with said seat, and yieldable means for normally holding said valve portion to said seat.

tory sleeve surrounding the nipple and the shoulder and provided at its lower end with an inwardly disposed annular rib forming an upwardly seating valve portion cooperating with said seat, and yieldable means for normally holding said valve portion to said seat.

13. A lubricator comprising a nipple projecting upwardly from the bottom thereof and having a valve seat portion, upwardly seating vibratory valve means cooperating with said seat portion, and adjustable spring means normally holding said valve portion to said seat.

14. In a lubricator, the combination of a nipple projecting above the bottom thereof and having a downwardly disposed valve seat at its upper end, a vibratory member having a valve portion cooperating with said seat, and a spring cooperating with said member to urge the valve portion against its seat.

15. In a lubricator, the combination of a nipple projecting above the bottom thereof and having a downwardly disposed valve seat at its upper end, a vibratory member having a valve portion adapted for rocking engagement with the seat, and a spring cooperating with the vibratory member to urge the valve portion against said seat.

16. In a lubricator, the combination of a nipple projecting above the bottom of the cup and having a valve seat at the upper end thereof and a hollow pendular member having a valve portion cooperating with said seat.

In testimony whereof I affix my signature.
ALLEN A. VAN ORSDALE.
